UNITED STATES PATENT OFFICE.

WILLIAM P. WOODS, OF EVANSVILLE, INDIANA.

DESIGN FOR A BADGE, EMBLEM, OR SIMILAR ARTICLE.

42,383.

Specification for Design.

Patented Apr. 2, 1912.

Application filed January 2, 1912. Serial No. 669,100. Term of patent 14 years.

To all whom it may concern:

Be it known that I, WILLIAM P. Woods, a citizen of the United States, residing at Evansville, in the county of Vanderburg and State of Indiana, have invented a new original, and ornamental Design for a Badge, Emblem, or Similar Article, of which the following is a specification.

The accompanying drawing is a plan view of a badge, emblem, or similar article, having my design applied thereto.

I claim:

The ornamental design for a badge, emblem, or similar article, as shown.

In testimony whereof I have hereunto set my hand in presence of two subscribing witnesses.

WILLIAM P. WOODS.

Witnesses:

LEONARD JAMES FOX,
ELIZABETH WAGNER.
